UNITED STATES PATENT OFFICE.

ROBERT K. JACK, OF LANSING, MICHIGAN, ASSIGNOR TO GENERAL MOTORS CORPORATION, OF DETROIT, MICHIGAN, A CORPORATION OF MICHIGAN.

CRANK-CASE-VENTILATING SYSTEM.

Application filed August 23, 1926. Serial No. 131,064.

This is an improvement on the invention disclosed in my prior application Serial No. 28,419, filed May 6, 1925. In that application I disclosed a crankcase ventilating system in which part of the carburetor air supply is taken from a hot air stove and the remaining part from the crankcase, the air supplied to the crank case to replace that withdrawn being cleaned by passage through an air cleaner. In this application I have disclosed a similar ventilating system in which a portion of the air supply after being cleaned in a large commercial type of air cleaner passes directly to the carburetor while the remainder of the air supply is obtained from the crankcase. To prevent dirt from entering the crankcase with the stream passing through to the carburetor I have provided the crankcase air inlet with an air cleaner. This cleaner may be of small capacity and of very simple type for the reason that the major portion of the carburetor air supply is taken through the main air cleaner, in actual practice about two-thirds of the total. With this system I have found by actual tests that there is a sufficient flow of air through the crankcase to remove the greater proportion of the diluents from the lubricated oil and yet neither the suction applied to the crankcase nor the velocity of the air stream flowing through it are sufficiently great to draw appreciable quantities of oil particles into the carburetor. Consequently clogging of the carburetor is avoided. To further insure against the passage of oil particles from the crankcase into the carburetor I have preferably employed the expedient also made use of in my prior construction of taking the vapors out of the crankcase by way of the valve chamber so that the valve mechanism acts after the manner of a baffle to intercept particles of oil. This also insures effective lubrication of the valve mechanism.

In the drawings:

Figure 1 is a side elevation of an engine provided with my ventilating system.

Figure 2 is a vertical section through the engine taken substantially on line 2-2 of Figure 1; and

Figure 3 is a section on line 3-3 of Figure 1.

Reference character 2 indicates an internal combustion engine of conventional type. The engine is provided with crankcase 4 which

serves as a lubricant reservoir, with valve chamber 6 communicating with the crankcase through openings 8 arranged about the valve tappet guides and with carburetor 10 which supplies fuel mixture to the engine through intake manifold 12.

Part of the carburetor air supply is taken directly from the atmosphere and the remainder from the crankcase. Thus 14 indicates the carburetor air intake and 16 indicates a fitting having branches 18 and 20. Branch 18 is secured to cover 21 of the valve chamber 6. To branch 16 is secured main air cleaner 22. This cleaner is preferably of the standard commercial type shown and claimed in the application of Herbert G. Kamrath Serial No. 75,071, filed Dec. 12, 1925. The cleaner draws its supply of air from the stream set in motion in the direction of arrow 24 by the usual cooling fan. Baffle 26 is provided so that the air entering the cleaner must make a sharp reverse turn which effectively eliminates the larger particles of dust. Upon entering the cleaner the air is given a spiral motion by means of suitable blades arranged at the forward end of the casing causing dust particles to follow the inner surface of the casing to a discharge port 28, the main air stream reversing in direction and passing out through the central passage 30 connected with branch 20 of fitting 16. If desired an air straightener may be provided in the passage 30 as shown in the said Kamrath application. While I have preferred to indicate a cleaner of the above type it is to be understood that any other suitable type may be employed.

An auxiliary air cleaner 32 is provided at the crankcase air inlet 34. This cleaner is of the general type described and claimed in the application of Herbert G. Kamrath, Serial No. 53,341, filed Aug. 29, 1925. For convenience it is mounted upon the upper end of oil gauge 36. This cleaner comprises a casing 36 having an open end 38 in which are arranged spiral blades 40. Through the opposite end of the casing protrudes pipe 42 through which air is discharged into the crankcase. At this end of the casing dust outlet 44 is provided. The end of the oil gauge 36 is secured to the pipe 42 by welding or the like. While I have described in detail a specific type of cleaner as well as a specific mounting for it, it is to be understood that so far as my invention is concerned any other suitable type of cleaner may be sub-

stituted and the mounting may be varied to suit the convenience of the particular engine. It will now be understood that the engine suction is effective at the carburetor air intake 14 to draw air both directly from the atmosphere and from the crankcase. The main air supply, which is preferably about two-thirds of the total, is cleaned by passage through cleaner 22 and in its passage through the fitting 16 produces an aspirating effect upon the open end of the conduit 18. To enhance this aspirating effect I have preferably provide baffle 50 which is in effect a continuation of the rear wall of branch 18. By the use 15 of this baffle the speed of flow of the main air supply is increased with resultant increase in aspirating effect.

Air entering the crankcase through inlet 34 is cleaned by passage through cleaner 32. In 20 the crankcase it is thoroughly mixed with the oil and vapors therein so that diluents such as gasoline and water are evaporated and carried along with the air stream through the valve chamber 6, where the heat of the cylinder walls serves to maintain the diluents in vapor form, and through branch 18 of fitting 25 20 into the carburetor air intake 14. In passing through the valve chamber the heavier particles of oil are intercepted in part by the

valve operating mechanism and serve to 30 effectively lubricate the latter.

I claim:

1. The combination of an engine provided with a crankcase and a carburetor, a conduit for supplying air to the carburetor, an air inlet for the crankcase, a conduit connecting the crankcase with said first named conduit for supplying crankcase vapors to the carburetor, and a baffle at the junction of said conduits for restricting the flow of air through the first 40 named conduit to increase the aspirating effect on said second named conduit. 35

2. In the combination as defined in claim 1, an air cleaner for said first named conduit, and an auxiliary air cleaner for said air inlet. 45

3. The combination of an engine provided with a crankcase and a carburetor, a main air cleaner, a conduit for connecting said cleaner with the carburetor, said crankcase being provided with an air inlet, an auxiliary air cleaner for said inlet, and a conduit connecting said crankcase with the carburetor independently of said air cleaner, said engine being provided with a valve chamber and said conduit communicating with the crankcase 50 through said chamber. 55

In testimony whereof I affix my signature.
ROBERT K. JACK.
